DESIGN FOR A KEY CHARM

James A. Murray, Philadelphia, Pa.

Application June 12, 1936, Serial No. 63,261

Term of patent 14 years

To all whom it may concern:

Be it known that I, James A. Murray, a citizen of the United States, residing at Philadelphia, in the county of Philadelphia and State of Pennsylvania, have invented a new, original, and ornamental Design for a Key Charm, of which the following is a specification, reference being had to the accompanying drawing, forming a part thereof.

I claim:

The ornamental design for a key charm, as shown.

J. A. MURRAY.
